[57] CLAIM

The ornamental design for a dining table, as shown and described.

DESCRIPTION

FIG. 1 is a perspective view of a dining table showing my new design with solid inlay in top and apron, and chamfered pierced legs;

FIG. 2 is a top plan view thereof;

FIG. 3 is a front elevational view thereof, the rear elevational view being identical; and,

FIG. 4 is a right side elevation thereof, the left side elevation being identical.

The bottom of the table is plain and unadorned.
